STETHOSCOPE WALL MOUNTED BRACKET

Ben Einhorn, 4858 Topeka Drive,
Tarzana, Calif. 91356

Filed July 28, 1971, Ser. No. 167,070

Term of patent 3½ years

Int. Cl. D24—99; D14—03
U.S. Cl. D83—1 F

FIG. 1 is a front elevational view of a stethoscope wall mounted bracket embodying my new design;

FIG. 2 is a top plan view;

FIG. 3 is a sectional view taken on line 1—1 of FIG. 1;

FIG. 4 is a perspective view of the same.

I claim:

The ornamental design for a stethoscope wall mounted bracket, substantially as shown and described.
